(57) **ABSTRACT**

The invention is a press-molding device which is configured to obtain a press-molded article with a hat-shaped cross section by compressing a preform with a hat-shaped cross section between a punch of a first mold and a die of a second mold. The press-molding device includes: a punch and a die forming a compression mechanism to compress a flange and a side wall of a hat-shape in the preform; a compression block forming a first pressing mechanism to press an outer end portion of the flange of the hat-shape in the preform; a pad forming a second pressing mechanism to press an upper end portion of the side wall of the hat-shape in the preform.

**METHOD FOR MANUFACTURING
PRESS-MOLDED ARTICLE, AND
PRESS-MOLDING DEVICE**

TECHNICAL FIELD

The present invention relates to a method for manufacturing a press-molded article, and a press-molding device.

BACKGROUND ART

Conventionally, there has been known a method for manufacturing a press-molded article in which a blank with a square U-shaped cross section obtained by subjecting a raw plate to a bending process or the like is subjected to such a process that vertical wall portions on the open side of the square U-shape are compressed between an upper mold and a lower mold in an up-down direction with lower ends of the vertical wall portions being in contact with the lower die (for example, see Patent Literature 1).

The manufacturing method as described above prevents spring-back that acts in such a way that the vertical wall portions spread away from each other, and can improve dimensional accuracy of the obtained press-molded article.

PRIOR ART LITERATURE

Patent Literature

Patent Literature 1: JP6527544B2

SUMMARY OF THE INVENTION

Problem to be Solved by the Invention

Many of long members generally used for a vehicle body frame and the like have a closed cross section structure obtained by fitting together half bodies (half shells) with hat-shaped cross sections and welding flanges corresponding to brim portions of the hat shapes to each other. Accordingly, it is desirable to prevent the spring-back also in the method for manufacturing the press-molded article with the hat-shaped cross section as described above.

However, in the method for manufacturing the press-molded article with the hat-shaped cross section, it is necessary to prevent not only the spring-back that acts in such a way that the vertical wall portions spread away from each other but also spring-back that acts in such a way that angles formed between the vertical wall portions and the flange portions increase. Accordingly, in the conventional method for manufacturing the press-molded article (for example, see Patent Literature 1), it is impossible to sufficiently improve the dimensional accuracy of the press-molded article with the hat-shaped cross section.

An object of the present embodiment is to provide a method for manufacturing a press-molded article, and a press-molding device that enable obtaining of a press-molded article with a hat-shaped cross section in which spring-back is sufficiently reduced and which has excellent dimensional accuracy, in simple steps.

Solution to Problem

A method for manufacturing a press-molded article of the present invention that solves the aforementioned problem is characterized in that a second bent plate body with a hat-shaped cross section is obtained by a first bent plate body

2

with a hat-shaped cross section is in-plane compressed between a first mold and a second mold, over a range from a side wall forming a crown portion of a hat shape in the first bent plate body with the hat-shaped cross section to a flange of the hat shape, along a peripheral length direction of the hat shape.

Moreover, a press-molding device of the present invention that solves the aforementioned problem is a press-molding device which obtains a second bent plate body with a hat-shaped cross section by compressing a first bent plate body with a hat-shaped cross section between a first mold and a second mold. Each of the bent plate bodies with the hat-shaped cross sections includes a side wall which is formed to correspond to a crown portion of a hat shape and which extends in a height direction of the crown portion and a flange which is formed to correspond to a brim portion of the hat shape and which extends outward from an end portion of the side wall on the open side of the crown portion to project in a direction away from the end portion. The first mold is formed of a punch and includes a first wall surface formed to correspond to a side wall of the second bent plate body with the hat-shaped cross section; and a second wall surface formed to correspond to a flange of the second bent plate body with the hat-shaped cross section. The first wall surface and the second wall surface form a first corner portion and are continuous with each other. The second mold is formed of a die and a third wall surface parallel to the first wall surface and a fourth wall surface parallel to the second wall surface. The third wall surface and the fourth wall surface form a second corner portion and are continuous with each other. The press-molding device includes: a compression mechanism to bring the first corner portion and the second corner portion close to each other and compresses the side wall of the first bent plate body with the hat-shaped cross section between the first wall surface and the third wall surface and the flange of the first bent plate body with the hat-shaped cross section between the second wall surface and the fourth wall surface; a first pressing mechanism to press an end portion of the flange on the opposite side to the first corner portion in the first bent plate body with the hat-shaped cross section toward the first corner portion; and a second pressing mechanism to press an end portion of the side wall on the opposite side to the first corner portion in the first bent plate body with the hat-shaped cross section toward the first corner portion.

Advantageous Effect of the Invention

The present invention provides a method for manufacturing a press-molded article, and a press-molding device which obtain a press-molded article with a hat-shaped cross section in which spring-back is sufficiently reduced and which has excellent dimensional accuracy, in simple steps.

BRIEF DESCRIPTION OF DRAWINGS

FIG. 1 is a partial perspective view illustrating an example of a press-molded article that can be obtained in a manufacturing method according to an embodiment of the present invention.

FIG. 2 is a configuration explanation diagram of a press-molding device according to the embodiment of the present invention.

FIG. 3 is a partial enlarged view of a III portion in FIG. 2.

FIG. 4A is a diagram explaining a step in the method for manufacturing the press-molded article according to the

embodiment of the present invention, and is a diagram illustrating a step of arranging a preform (first bent plate body with a hat-shaped cross section) that is a compression material, on a punch.

FIG. 4B is a diagram explaining a step in the method for manufacturing the press-molded article according to the embodiment of the present invention, and is a diagram illustrating a step of pressing end portions of sprung-back flanges in the preform (first bent plate body with the hat-shaped cross section) that is the compression material, in a plane direction.

FIG. 4C is a diagram explaining a step in the method for manufacturing the press-molded article according to the embodiment of the present invention, and is a diagram explaining a step of compressing side walls of the preform (first bent plate body with the hat-shaped cross section).

FIG. 4D is a diagram explaining a step in the method for manufacturing the press-molded article according to the embodiment of the present invention, and is a diagram illustrating how the side walls of the preform (first bent plate body with the hat-shaped cross section) are in-plane compressed.

FIG. 4E is a diagram explaining a step in the method for manufacturing the press-molded article according to the embodiment of the present invention, and is a diagram illustrating how the press-molded article (second bent plate body with a hat-shaped cross section) is obtained in the mold.

FIG. 5A is a diagram explaining a configuration of a modified example of the press-molding device in the present invention.

FIG. 5B is a diagram explaining an operation of the press-molding device according to the modified example of FIG. 5A.

EMBODIMENT FOR CARRYING OUT THE INVENTION

Next, a method for manufacturing a press-molded article (hereinafter, simply referred to as press-molding method in some cases) in a mode for carrying out the present invention (present embodiment) and a press-molding device for carrying out this method are described in detail with reference to the drawings as appropriate.

The press-molding method of the present embodiment is a method in which, for example, a preform with a hat-shaped cross section made of a plate material such as a steel plate is in-plane compressed in a mold and a final molded article with a hat-shaped cross section is obtained.

An example of the press-molded article obtained in the present embodiment is described below, and then the press-molding device and the press-molding method are described. Note that directions of up and down in the following description are based on directions of up and down of the press-molding device. Moreover, directions of up and down in the press-molded article coincide with up and down directions of the press-molded article obtained in the press-molding device.

<Press-Molded Article>

FIG. 1 is a partial enlarged perspective view illustrating an example of a press-molded article 10 that can be obtained in the press-molding method according to the present embodiment.

The press-molded article 10 in the present embodiment is assumed to be an elongated structural member made of a high-tensile strength steel plate and used in a vehicle body frame of an automobile or the like. However, the press-

molded article 10 is not limited to this, and the present embodiment can be applied to structural members made of various metal materials used in various fields. Note that a portion of the press-molded article 10 in FIG. 1 is drawn to be cut out for convenience of illustration drawing a horizontal cross section.

As illustrated in FIG. 1, the press-molded article 10 is a member (long member) elongated in one direction, and a horizontal cross section intersecting a longitudinal direction has a hat shape.

The hat shape includes paired side walls 13a and 13b forming side surfaces of a crown portion 11, a top portion 14 of the crown portion 11 coupling one end sides (upper end sides) of the paired side walls 13a and 13b to each other, and paired flanges 15a and 15b forming a brim portion 12 (brim), as well known.

The crown portion 11 has a substantially square U-shape (substantially U-shape) in which the one end sides of the paired side walls 13a and 13b are closed on the top portion 14 side and the other end sides (lower end sides) of the side walls 13a and 13b are opened. The flanges 15a and 15b are formed to protrude outward (in directions away from the opening) from end edges (lower edges) of the respective paired side walls 13a and 13b on the open side of the crown portion 11 having the substantially square U-shape (substantially U-shape).

The top portion 14 of the crown portion 11 in the present embodiment is configured to include a horizontal wall 16 laid to be connected to the one ends of the paired side walls 13a and 13b via chamfered portions 17a and 17b.

Although the chamfered portions 17a and 17b forming the top portion 14 in the present embodiment are formed to be such tilted surfaces that a width between the chamfered portions 17a and 17b becomes gradually smaller as the chamfered portions 17a and 17b extend from the one ends of the paired side walls 13a and 13b toward the upper side, the chamfered portions 17a and 17b may be formed to be curved surfaces (rounded surfaces) bulging upward, instead of the tilted surfaces.

Moreover, the mode of the top portion 14 may be such that the horizontal wall 16 is connected to the one ends of the side walls 13a and 13b while forming predetermined angles therewithout the chamfered portions 17a and 17b or the curved surfaces (illustration is omitted).

Furthermore, although the press-molded article 10 of the present embodiment is assumed to have the hat-shaped horizontal cross section over the entire length in the longitudinal direction, a portion of the press-molded article 10 in the longitudinal direction may have the hat-shaped horizontal cross section. Moreover, each of the side walls 13a and 13b and the horizontal wall 16 is not limited to a wall having a flat-plate shape along the longitudinal direction, and a wall including a curved surface that is curved to warp with respect to the longitudinal direction is also acceptable. Furthermore, each of the side walls 13a and 13b and the horizontal wall 16 may be a wall including some unevenness such as a step or a bead formed in a plane direction. Moreover, a hole portion extending through the wall in a plate-thickness direction may be formed in each of the side walls 13a and 13b and the horizontal wall 16.

Furthermore, although the press-molded article 10 in the present embodiment is assumed to be an article in which one side wall 13a out of the paired side walls 13a and 13b has a smaller length than the other side wall 13b in the height direction (up-down direction) of the crown portion 11, the paired side walls 13a and 13b may have the same length.

Moreover, although the press-molded article 10 in the present embodiment is assumed to be an article in which the paired flanges 15a and 15b have the same horizontal width (length in the direction intersecting the longitudinal direction), the horizontal widths of the paired flanges 15a and 15b may vary from each other.

In the press-molded article 10 in the present embodiment, the flanges 15a and 15b are connected to another prepared member (illustration is omitted) by spot welding or the like, and a closed cross section is thereby formed between the other prepared member and an inside of the crown portion 11.

Note that examples of the other prepared member include, but not limited to, three-dimensional structures such as a floor panel of a vehicle body, a panel member forming a dashboard lower portion, and another hat-shaped member (half body) fitted and joined to the press-molded article 10 that is the other half body.

The aforementioned press-molded article 10 that is the final molded article is molded by using a press-molding device 30 (see FIG. 2) to be described later, and corresponds to a "second bent plate body with a hat-shaped cross section" described in the scope of claims.

The press-molded article 10 varies from a preform 20 (see FIG. 4A) supplied as a material to the press-molding device 30 to obtain the press-molded article 10. The preform 20 corresponds to a "first bent plate body with a hat-shaped cross section" described in the scope of claims. The preform 20 is described in detail later together with description of the "press-molding method".

<Press-Molding Device>

FIG. 2 is a configuration explanation diagram of the press-molding device 30 according to the present embodiment. FIG. 2 schematically illustrates appearance of the press-molding device 30 from the front side.

As illustrated in FIG. 2, the press-molding device 30 is configured to mainly include a punch 31, paired dies 32a and 32b, a cam mechanism 40 that drives each of the dies 32a and 32b, and a pad 35a that performs holding of the later-described preform 20 (see FIG. 4A) arranged on the punch 31 and pressing of side walls 23a and 23b (see FIG. 4A).

The press-molding device 30 of the present embodiment is configured to in-plane compress the side walls 23a and 23b (see FIG. 4A) and flanges 25a and 25b (see FIG. 4A) in the preform 20 (see FIG. 4A) with the punch 31, the dies 32a and 32b, and the pad 35a as described in detail later.

(Punch and Dies)

The punch 31 in the present embodiment is assumed to be a fixed mold, and corresponds to a "first mold" in the scope of claims. Moreover, the dies 32a and 32b in the present embodiment are assumed to be movable molds and correspond to a "second mold" in the scope of claims. Note that the press-molding device 30 may be configured such that the dies 32a and 32b are set on the fixed side and the punch 31 is set on the movable side.

FIG. 3 is a partial enlarged view of a III portion in FIG. 2.

As illustrated in FIG. 3, the punch 31 in the present embodiment has a compression molding surface modeled after a recess surface 19 out of a protruding surface 18 and the recess surface 19 of the press-molded article 10 (see FIG. 1) having the hat-shaped cross section and elongated in one direction.

The punch 31 (see FIG. 3) is formed in a rail shape elongated in one direction (direction perpendicular to the sheet surface of FIG. 3) to match the press-molded article 10 (see FIG. 1).

Specifically, as illustrated in FIG. 3, the punch 31 includes a base portion 31a formed of a substantially-cuboid elongated body and a projecting portion 31b formed of a substantially-cuboid elongated body. The projecting portion 31b is formed to project upward at the center of the base portion 31a in the width direction thereof (left-right direction in the sheet surface of FIG. 3) while having a smaller width than the base portion 31a.

The punch 31 of the present embodiment as described above includes first wall surfaces 53a and 53b of the projecting portion 31b that correspond respectively to the side walls 13a and 13b (see FIG. 1) in the crown portion 11 (see FIG. 1) of the press-molded article 10 and second wall surfaces 55a and 55b of the base portion 31a that correspond to the flanges 15a and 15b (see FIG. 1).

The first wall surface 53a is continuous with the second wall surface 55a via a first corner portion 58a, and the first wall surface 53b is continuous with the second wall surface 55b via a first corner portion 58b.

Note that the base portion 31a includes an outer end surface 36a that intersects the second wall surface 55a on the opposite side to the first corner portion 58a. Moreover, the base portion 31a includes an outer end surface 36b that intersects the second wall surface 55b on the opposite side to the first corner portion 58b. The outer end surfaces 36a and 36b are formed to extend in the vertical direction.

Fifth wall surfaces 37a and 37b of compression blocks 34a and 34b are capable of coming into contact with the respective outer end surfaces 36a and 36b in the base portion 31a, at lower dead points of the dies 32a and 32b to be described later.

In the punch 31, a top portion 31c is formed to correspond to the top portion 14 (see FIG. 1) of the press-molded article 10 (see FIG. 1). Specifically, in the punch 31, a horizontal wall 56 is formed to correspond to the horizontal wall 16 (see FIG. 1) of the press-molded article 10 (see FIG. 1). Moreover, in the punch 31, tilted wall surfaces 57a and 57b are formed to correspond to the chamfered portions 17a and 17b (see FIG. 1) of the press-molded article 10 (see FIG. 1). Furthermore, the tilted wall surfaces 57a and 57b are continuous with the first wall surfaces 53a and 53b while forming predetermined angles therewith.

A length along the one second wall surface 55a, the one first corner portion 58a, the one first wall surface 53a, and the one tilted wall surface 57a, the horizontal wall 56, the other tilted wall surface 57b, the other first wall surface 53b, the other first corner portion 58b, and the second wall surface 55b of the punch 31 as described above, that is the peripheral length of the punch 31 is set to be equal to the peripheral length of the press-molded article 10 corresponding to the punch 31.

Next, the dies 32a and 32b are described.

As illustrated in FIG. 2, the dies 32a and 32b in the present embodiment are integral respectively with later-described cam sliders 41a and 41b of the cam mechanism 40 that can move forward and backward at predetermined angles with respect to a compression molding surface of the punch 31.

The dies 32a and 32b are arranged in a pair respectively at such positions that the projecting portion 31b of the punch 31 is provided at the center between the dies 32a and 32b in the horizontal direction (left-right direction in the sheet surface of FIG. 2). Specifically, the dies 32a and 32b are

each formed of a long member elongated in one direction (direction perpendicular to the sheet surface of FIG. 2) to correspond to the rail-shaped punch 31.

To be more specific, in the front view illustrated in FIG. 3, the die 32a and the die 32b are arranged to be substantially line symmetric to each other with respect to a center axis Ax of the projecting portion 31b extending in the up-down direction. Note that the center axis Ax of the projecting portion 31b in the present embodiment can be defined as an axis extending in the vertical direction (coincides with the up-down direction in FIG. 3) at the center of the horizontal wall 56 in the horizontal direction (left-right direction in the sheet surface of FIG. 2).

The die 32a includes a die main body 33a and the compression block 34a integrally attached to the die main body 33a. The die 32b includes a die main body 33b and the compression block 34b integrally attached to the die main body 33b.

One die main body 33a arranged to correspond to the one first wall surface 53a in the punch 31 includes a third wall surface 63a parallelly facing the first wall surface 53a. Moreover, the other die main body 33b arranged to correspond to the other first wall surface 53b in the punch 31 includes a third wall surface 63b parallelly facing the first wall surface 53b.

Moreover, the one die main body 33a includes a fourth wall surface 65a that is parallel to the one second wall surface 55a of the punch 31 and that is continuous with the third wall surface 63a via a second corner portion 68a. The other die main body 33b includes a fourth wall surface 65b that is parallel to the other second wall surface 55b of the punch 31 and that is continuous with the third wall surface 63b via a second corner portion 68b.

The peripheral length of the die main body 33a from the third wall surface 63a to the fourth wall surface 65a via the second corner portion 68a in the one die main body 33a as described above is set to be equal to the peripheral length of the punch 31 from the first wall surface 53a to the second wall surface 55a via the first corner portion 58a in the punch 31.

Moreover, the peripheral length of the die main body 33b from the third wall surface 63b to the fourth wall surface 65b via the second corner portion 68b in the other die main body 33b is set to be equal to the peripheral length of the punch 31 from the first wall surface 53b to the second wall surface 55b via the first corner portion 58b in the punch 31.

Next, the compression blocks 34a and 34b are described.

As illustrated in FIG. 3, the compression block 34a is arranged to be integral with the die main body 33a at a base end of the die main body 33a located on the cam slider 41a side to be described later, below the die main body 33a. Moreover, the compression block 34b is arranged to be integral with the die main body 33b, at a base end of the die main body 33b located on the cam slider 41b side to be described later, below the die main body 33b.

Each of the compression blocks 34a and 34b in the present embodiment is assumed to be a block body formed of a substantially-cuboid body elongated in one direction (direction perpendicular to the sheet surface of FIG. 3) to correspond to the press-molded article 10. Note that the compression blocks 34a and 34b in the present embodiment are assumed to have a configuration in which blocks separate from the die main bodies 33a and 33b are attached to the die main bodies 33a and 33b. However, each of the compression blocks 34a and 34b may be a block integrally molded with a corresponding one of the die main bodies 33a and 33b.

In the compression block 34a as described above, the fifth wall surface 37a parallelly facing the outer end surface 36a of the base portion 31a is formed. Moreover, in the compression block 34b, the fifth wall surface 37b parallelly facing the outer end surface 36b of the base portion 31a is formed.

The fifth wall surfaces 37a and 37b of the compression blocks 34a and 34b as described above can come into contact respectively with the outer end surfaces 36a and 36b of the punch 31, at the lower dead points of the dies 32a and 32b as described later.

(Cam Mechanism)

Next, the cam mechanism 40 (see FIG. 2) is described.

As illustrated in FIG. 2, the cam mechanism 40 is configured to mainly include the paired cam sliders 41a and 41b provided to correspond respectively to the aforementioned dies 32a and 32b, paired cam bases 42a and 42b provided to correspond to these cam sliders 41a and 41b, and paired cam drivers 43a and 43b provided to correspond to the cam sliders 41a and 41b.

Note that the cam sliders 41a and 41b, the cam bases 42a and 42b, and the cam drivers 43a and 43b are formed of long members elongated in one direction (direction perpendicular to the sheet surface of FIG. 2) to correspond to the dies 32a and 32b.

The cam slider 41a moves the die 32a toward the punch 31 or moves the die 32a away from the punch 31 by climbing or descending a tilted surface 45a of the cam base 42a in a tilted direction.

Moreover, the cam slider 41b moves the die 32b toward the punch 31 or moves the die 32b away from the punch 31 by climbing or descending a tilted surface 45b of the cam base 42b in a tilted direction.

Specifically, the cam sliders 41a and 41b move the respective dies 32a and 32b toward the punch 31 at angles θ_a and θ_b each formed between the horizontal plane Hp and a corresponding one of the tilted surfaces 45a and 45b on the narrow angle side.

Note that each of the angles θ_a and θ_b may be set within a range of more than 0 degrees to less than 90 degrees (0° (deg) $< \theta_a, \theta_b < 90^\circ$ (deg)), but is preferably 15 degrees or more and 60 degrees or less, particularly preferably about 15 degrees. The angles θ_a and θ_b may be the same or vary from each other. Note that the angles θ_a and θ_b in the present embodiment are both assumed to be 15 degrees.

The cam bases 42a and 42b support the respective cam sliders 41a and 41b such that the cam sliders 41a and 41b can move by sliding along the respective tilted surfaces 45a and 45b.

Note that the cam bases 42a and 42b in the present embodiment are integrally formed. A center portion where the cam bases 42a and 42b are connected to one another also serves as a supporting portion of the punch 31.

Furthermore, the cam bases 42a and 42b, respectively, include biasers 46a and 46b using coil springs or the like that bias the respective cam sliders 41a and 41b in directions away from the punch 31. Note that these biasers 46a and 46b are not limited to particular means and may be, for example, a well-known structure in which springs S are arranged between the cam base 42a and the cam slider 41a and between the cam base 42b and the cam slider 41b. Examples of the springs S include gas springs, coil springs, and the like.

A plurality of the biasers 46a or 46b as described above are assumed to be arranged along the longitudinal direction (direction perpendicular to the sheet surface of FIG. 2) of each of the cam bases 42a and 42b.

The cam drivers 43a and 43b in the present embodiment, together with a pad unit 35 including the pad 35a to be described later, form a substantially E-shape open on the lower side in the front view of the press-molding device 30 illustrated in FIG. 2. Specifically, the cam drivers 43a and 43b are each connected to a pad support portion 35c that extends in the horizontal direction below a lifting-lowering mechanism 39 to be described later and that can move up and down.

To be more specific, upper end portions of the respective cam drivers 43a and 43b are connected to the pad support portion 35c such that the pad unit 35 is arranged at the center between the cam drivers 43a and 43b. The cam drivers 43a and 43b extend downward from the pad support portion 35c and form cam surfaces 44a and 44b that drive the cam sliders 41a and 41b.

The cam surfaces 44a and 44b are formed on lower end surfaces of the cam drivers 43a and 43b facing the cam sliders 41a and 41b.

Each of the cam surfaces 44a and 44b is configured to be a tilted surface whose position gradually becomes lower while extending away from the pad 35a arranged at the center between the cam surfaces 44a and 44b.

Slide members 47a and 47b that guide the cam sliders 41a and 41b along the cam surfaces 44a and 44b by sliding relative to the cam surfaces 44a and 44b are attached to upper surfaces of the respective cam sliders 41a and 41b.

These cam drivers 43a and 43b move the respective cam sliders 41a and 41b toward the punch 31 via the cam surfaces 44a and 44b when the lifting-lowering mechanism 39 including, for example, a hydraulic cylinder or the like moves the pad support portion 35c downward. Specifically, the cam surfaces 44a and 44b thrust the respective cam sliders 41a and 41b toward the punch 31 at the aforementioned angles θ_a and θ_b against biasing force of the biasers 46a and 46b.

Conversely, when the lifting-lowering mechanism 39 moves the pad support portion 35c upward, the pressing force (thrusting force) of the cam surfaces 44a and 44b on the cam sliders 41a and 41b is released. The cam sliders 41a and 41b are thereby restored to original positions by the biasing force of the biasers 46a and 46b.

(Pad)

Next, the pad 35a (see FIG. 2) is described.

The pad 35a in the present embodiment is configured of a substantially-cuboid block elongated in one direction (direction perpendicular to the sheet surface of FIG. 2) to correspond to the press-molded article 10 (see FIG. 1).

As illustrated in FIG. 2, the pad 35a is attached to the pad support portion 35c via a later-described cushion member 35b, to be located above the punch 31.

As illustrated in FIG. 3, the pad 35a includes a groove portion 35d into which the top portion 31c of the punch 31 fits, in a lower end portion facing the punch 31. The groove portion 35d is formed to extend in one direction (direction perpendicular to the sheet surface of FIG. 3) to correspond to the press-molded article 10 (see FIG. 1).

Specifically, the groove portion 35d includes a bottom surface 35d1 formed to correspond to the horizontal wall 16 (see FIG. 1) of the press-molded article 10 (see FIG. 1) and side surfaces 35d2 and 35d3 formed to correspond to the chamfered portions 17a and 17b (see FIG. 1) of the press-molded article 10 (see FIG. 1).

Although the cushion member 35b (see FIG. 2) in the present embodiment is assumed to be a coil spring, another spring such as a gas spring may also be used as the cushion member 35b.

As illustrated in FIG. 2, the cushion member 35b in the present embodiment is housed above the groove portion 35d, in a cylindrical space 35e formed to extend in the up-down direction of the pad 35a. The lower end of the cushion member 35b is attached to a spring seat (illustration is omitted) provided in a bottom portion of the cylindrical space 35e, and the upper end of the cushion member 35b is attached to the pad support portion 35c.

Note that a plurality of the cushion members 35b as described above are arranged in the longitudinal direction (direction perpendicular to the sheet surface of FIG. 3) of the pad 35a.

The spring constant of the cushion member 35b is adjusted such that the cushion member 35b has room to contract until the pad 35a transitions from a state where the pad 35a is out of contact with the punch 31 as illustrated in FIG. 2 to a state where the pad 35a (see FIG. 4C) starts compression molding on a top portion 24 (see FIG. 4C) of the preform 20 (see FIG. 4C). Moreover, the cushion member 35b cannot contract until the pad 35a transitions from the state (see FIG. 4C) where the pad 35a starts the compression molding on the top portion 24 (see FIG. 4C) to at least a state (see FIG. 4E) where the pad 35a reaches the lower dead point thereof. Furthermore, the spring constant of the cushion member 35b is adjusted such that the pad 35a can hold the top portion 24 (see FIG. 4A) of the preform 20 (see FIG. 4A) from the state illustrated in FIG. 2 to the state illustrated in FIG. 4C.

<Press-Molding Method>

Next, the press-molding method according to the present embodiment executed by the press-molding device 30 (see FIG. 2) according to the present embodiment is described while giving description of operations of the press-molding device 30.

FIGS. 4A to 4E are diagrams explaining steps of the press-molding method.

FIG. 4A is a diagram illustrating a step (first step) of arranging the preform 20 (first bent plate body with the hat-shaped cross section) on the punch 31. FIG. 4B is a diagram illustrating a step (second step) of pressing end portions of the sprung-back flanges 25a and 25b in the preform 20 (first bent plate body with the hat-shaped cross section) in in-plane directions of the flanges 25a and 25b. FIG. 4C is a diagram explaining a step (third step) of compressing the side walls 23a and 23b of the preform (first bent plate body with the hat-shaped cross section). FIG. 4D is a diagram illustrating how the side walls 23a and 23b of the preform 20 (first bent plate body with the hat-shaped cross section) are in-plane compressed. FIG. 4E is a diagram illustrating how the press-molded article 10 (second bent plate body with the hat-shaped cross section) is obtained in the mold (punch 31, dies 32a and 32b). (First Step)

As illustrated in FIG. 4A, in the first step of the press-molding method in the present embodiment, the preform 20 is arranged on the punch 31.

The preform 20 (first bent plate body with the hat-shaped cross section) corresponds to the "first bent plate body with the hat-shaped cross section" described in the scope of claims as described above.

Note that FIG. 4A illustrates a state where the top portion 24 of the preform 20 is held at the pad 35a by lowering the lifting-lowering mechanism 39 after arranging the preform 20 on the punch 31 in the state where the pad 35a and the punch 31 are out of contact with each other as illustrated in FIG. 2.

The preform 20 that is the material for obtaining the press-molded article 10 (see FIG. 1) can be manufactured by supplying a blank of, for example, a high-tensile strength steel plate to, for example, a press-molding device including a die (illustration is omitted) that has a compression molding surface modeled after the protruding surface 18 (see FIG. 1) side of the press-molded article 10 and a punch (illustration is omitted) that has a compression molding surface modeled after the recess surface 19 (see FIG. 1) side of the press-molded article 10.

In the preform 20 as described above, so-called spring back occurs mainly due to stress generated in bent portions of the blank.

Specifically, as illustrated in FIG. 4A, when the top portion 24 is held on the upper portion of the punch 31 at the pad 35a, the preform 20 is in a state where the side walls 23a and 23b of the preform 20 are lifted from the first wall surfaces 53a and 53b of the punch 31, respectively.

Note that, in the first step of the present embodiment, there is prepared the preform 20 in which the side walls 23a and 23b are longer than the side walls 13a and 13b (see FIG. 1) of the press-molded article 10 (see FIG. 1), respectively, as illustrated in FIG. 4A. Meanwhile, the lengths of the flanges 25a and 25b of the preform 20 are about the same as the lengths of the flanges 15a and 15b (see FIG. 1) of the press-molded article 10 (see FIG. 1), respectively.

Note that the preform 20 is not limited to the aforementioned design, and the lengths of the flanges 25a and 25b may be changed as described later as another embodiment of the present invention.

(Second Step)

Next, the second step of the press-molding method in the present embodiment is described.

In the second step, as illustrated in FIG. 4B, the compression blocks 34a and 34b press outer end portions 28a and 28b of the sprung-back flanges 25a and 25b.

In the second step, first, when the lifting-lowering mechanism 39 (see FIG. 2) moves the pad support portion 35c (see FIG. 2) downward from the state where the position of the pad 35a is that illustrated in FIG. 4A, the pad 35a comes into contact with the top portion 24 of the preform as illustrated in FIG. 4B. In this case, as illustrated in FIG. 4B, the cushion member 35b presses the top portion 24 of the preform 20 more strongly via the pad 35a while shrinking.

Meanwhile, the downward moving of the pad support portion 35c (see FIG. 2) by the lifting-lowering mechanism 39 (see FIG. 2) causes the cam drivers 43a and 43b illustrated in FIG. 2 to move the respective cam sliders 41a and 41b toward the punch 31.

The dies 32a and 32b provided in the cam sliders 41a and 41b thereby come close to the punch 31 as illustrated in FIG. 4B.

Specifically, the second corner portions 68a and 68b of the dies 32a and 32b move to come close to the first corner portions 58a and 58b of the punch 31.

Then, the fifth wall surfaces 37a and 37b of the compression blocks 34a and 34b press the outer end portions 28a and 28b of the flanges 25a and 25b in the preform 20 toward the first corner portions 58a and 58b of the punch 31, respectively.

Note that the dies 32a and 32b (compression blocks 34a and 34b) that press the flanges 25a and 25b, the cam mechanism 40, and the lifting-lowering mechanism 39 form a “first pressing mechanism” described in the scope of claims.

(Third Step)

Next, the third step of compressing the side walls 23a and 23b of the preform 20 (first bent plate body with the hat-shaped cross section) is described.

In the third step, as illustrated in FIG. 4C, a gap G is formed between the punch 31 and the top portion 24 of the preform 20.

The compression blocks 34a and 34b further press the outer end portions 28a and 28b of the flanges 25a and 25b, respectively, from the positions of the compression blocks 34a and 34b illustrated in FIG. 4B, and the gap G is thereby formed.

Specifically, as illustrated in FIG. 4C, the top portion 24 of the preform 20 lifts the pad 35a upward with the gap G formed as an escape margin of an excessive portion of the preform 20 squeezed into a space between the die 32a (illustration of the die 32b is omitted) and the punch 31 at the compression block 34a (illustration of the compression block 34b is omitted).

Then, when the lifting-lowering mechanism 39 (see FIG. 2) moves the pad support portion 35c downward from the state where the position of the pad 35a is that illustrated in FIG. 4C, the cushion member 35b that cannot contract causes the pad 35a to press the top portion 24 of the preform downward. Upper end portions 29a and 29b of the side walls 23a and 23b are thereby pressed toward the first corner portions 58 of the punch 31.

The pad 35a that presses the upper end portions 29a and 29b of the side walls 23a and 23b as described above and the lifting-lowering mechanism 39 (see FIG. 2) form a “second pressing mechanism” described in the scope of claims.

In the third step, in the cam drivers 43a and 43b (see FIG. 2), the lifting-lowering mechanism 39 (see FIG. 2) moves the pad support portion 35c (see FIG. 2) downward. As illustrated in FIG. 4D, the second corner portions 68a and 68b in the dies 32a and 32b provided in the cam sliders 41a and 41b thereby move to come close to the first corner portions 58a and 58b of the punch 31. The side walls 23a and 23b and the flanges 25a and 25b of the preform 20 (first bent plate body with the hat-shaped cross section) are thereby compressed between the punch 31 and the dies 32a and 32b.

The press-molding method of the present embodiment is configured such that the third step of compressing the side walls 23a and 23b and the flanges 25a and 25b of the preform 20 between the punch 31 and the dies 32a and 32b illustrated in FIG. 4D is performed in parallel with the second step of pressing the outer end portions 28a and 28b of the flanges 25a and 25b of the preform 20 toward the first corner portions 58 of the punch 31 illustrated in FIG. 4B.

Specifically, as illustrated in FIG. 4D, the preform 20 (first bent plate body with the hat-shaped cross section) with a larger peripheral length than the peripheral length of the punch 31 is squeezed on the punch 31 such that an excessive length is resolved according to the peripheral length of the punch 31.

The flanges 25a and 25b and the side walls 23a and 23b of the preform 20 are thereby in-plane compressed in the peripheral length direction of the hat shape of the preform 20.

Then, as illustrated in FIG. 4E, the in-plane compressed flanges 25a and 25b and the side walls 23a and 23b form the flanges 15a and 15b and the side walls 13a and 13b, respectively, and the press-molded article 10 is formed in the mold formed of the punch 31, the dies 32a and 32b, and the pad 35a.

<<Operational Effects>>

Next, operational effects provided by the press-molding method and the press-molding device 30 of the present embodiment are described.

In the press-molding method of the present embodiment, the press-molded article 10 (second bent plate body with the hat-shaped cross section) is obtained by in-plane compressing the side walls 23a and 23b and the flanges 25a and 25b of the preform 20 (first bent plate body with the hat-shaped cross section) along the peripheral length direction of the hat shape.

According to the press-molding method as described above, when the side walls 23a and 23b and the flanges 25a and 25b are in-plane compressed along the peripheral length direction of the hat shape, stress generated in the bent portions in the hat shape is canceled out. The press-molding method in the present embodiment can thereby eliminate spring back generated in the preform 20 in a simple step such a compression molding process, unlike in a conventional press-molding method (for example, see Patent Literature 1) in a conventional deep drawing process.

The press-molded article 10 obtained by this press-molding method has excellent dimensional accuracy due to reduction of the spring back.

Moreover, in the press-molding method of the present embodiment, the third step of compressing the side walls 23a and 23b and the flanges 25a and 25b of the preform 20 between the punch 31 and the dies 32 is performed in parallel with the second step of pressing the outer end portions 28a and 28b of the flanges 25a and 25b of the preform 20 toward the first corner portions 58 of the punch 31.

In the press-molding method as described above, the in-plane compression can be performed on the side walls 23a and 23b and the flanges 25a and 25b of the preform 20 (first bent plate body with the hat-shaped cross section) in a simpler step.

The press-molding device 30 of the present embodiment includes a compression mechanism that includes the dies 32a and 32b and the punch 31 configured to compress the side walls 23a and 23b and the flanges 25a and 25b of the preform 20, a first pressing mechanism that presses the outer end portions 28a and 28b of the flanges 25a and 25b, and the second pressing mechanism that presses the upper end portions 29a and 29b of the side walls 23a and 23b.

According to the press-molding device 30 as described above, it is possible to obtain the aforementioned operational effects of the press-molding method and execute the aforementioned press-molding method in a simple configuration.

In the press-molding device 30 of the present embodiment, the first pressing mechanism and the second pressing mechanism are interlocked with each other via the cam mechanism 40.

According to the press-molding device 30 as described above, when the compression step of the flanges 25a and 25b and the side walls 23a and 23b is executed, control of the step of pressing the outer end portions 28a and 28b of the flanges 25a and 25b and the step of pressing the upper end portions 29a and 29b of the side walls 23a and 23b that are performed together with the compression step is simplified. The in-plane compression of the flanges 25a and 25b and the side walls 23a and 23b can be thereby more accurately executed.

In the press-molding device 30 of the present embodiment, the first pressing mechanism includes the fifth wall surfaces 37a and 37b that come close to the outer end

surfaces 36a and 36b of the punch 31 as the second corner portions 68a and 68b of the dies 32a and 32b and the first corner portions 58a and 58b of the punch 31 relatively come close to one another. Specifically, the fifth wall surfaces 37a and 37b of the compression blocks 34a and 34b forming the first pressing mechanism form the dies 32a and 32b together with the die main bodies 33a and 33b.

According to the press-molding device 30 as described above, it is possible to interlock the compression mechanism 10 formed of the dies 32a and 32b and the punch 31 with the first pressing mechanism that presses the outer end portions 28a and 28b of the flanges 25a and 25b.

This can simplify the configurations of the compression mechanism and the first pressing mechanism, and achieve 15 size reduction of the press-molding device 30.

In the press-molding device 30 of the present embodiment, the aforementioned second pressing mechanism is the pad 35a that presses the top portion 31c of the preform 20 when the second corner portions 68a and 68b of the dies 32a and 32b and the first corner portions 58a and 58b of the punch 31 relatively come close to one another.

According to the press-molding device 30 as described above, it is possible to interlock the compression mechanism formed of the dies 32a and 32b and the punch 31 and the second pressing mechanism formed of the pad 35a with each other.

This can simplify the configurations of the compression mechanism and the second pressing mechanism, and achieve size reduction of the press-molding device 30.

Although the embodiment of the present invention has been described above, the present invention is not limited to the aforementioned embodiment, and various changes can be made within a scope not departing from the gist of the present invention.

FIG. 5A is a diagram explaining a configuration of a first modified example of the press-molding device 30. FIG. 5B is a diagram explaining an operation of the press-molding device 30 according to the first modified example of FIG. 5A.

As illustrated in FIG. 5A, in the press-molding device 30 according to the first modified example, the punch 31 is divided into two parts of an upper punch 311 and a lower punch 312.

A lifter 313 is arranged between the upper punch 311 and the lower punch 312. Note that the lifter 313 is formed of a cushion member such as, for example, a coil spring.

The lifter 313 is configured to lift the upper punch 311 by using biasing force such that a predetermined gap is opened upward when the first step illustrated in FIG. 4A is performed, the upper punch 311 holding the top portion 24 of the preform 20 between itself and the pad 35a.

Then, in the press-molding device 30 according to the first modified example, when the pad 35a presses down the top portion 24 of the preform 20 against the biasing force of the lifter 313 as illustrated in FIG. 5B, the gap between the upper punch 311 and the lower punch 312 disappears.

The pad 35a thereby presses the upper end portions 29a and 29b of the side walls 23a and 23b toward the first corner portions 58a and 58b of the punch 31 when the side walls 23a and 23b and the flanges 25a and 25b are compressed between the punch 31 and the dies 32a and 32b.

According to the press-molding device 30 in the first modified example as described above, the press-down amount of the upper end portions 29a and 29b by the pad 35a can be defined by using the gap between the upper punch 311 and the lower punch 312. Accordingly, it is possible to set the press-down amount to a fixed amount.

Note that reference signs 34a and 34b in FIG. 5B denote the compression blocks.

Although the first wall surfaces 53a and 53b of the punch 31 in the press-molding device 30 (see FIG. 3) of the aforementioned embodiment are tilted such that a distance 5 between the first wall surfaces 53a and 53b gradually becomes smaller toward the upper side, tilting of the first wall surfaces 53a and 53b relative to each other is not limited to particular tilting.

Specifically, in the press-molding device 30, the compression blocks 34a and 34b are arranged on the dies 32a and 32b sides. Accordingly, the first wall surfaces 53a and 53b may be parallel to each other in the front view of the press-molding device 30 illustrated in FIG. 3, or form an undercut in an opposite manner to the first wall surfaces 53a and 53b illustrated in FIG. 3.

Note that the first wall surfaces 53a and 53b forming the undercut can be subjected to prospect molding.

Moreover, although illustration is omitted, accuracy assurance of a press-molded article that has a vertical wall 20 or a wall close to vertical needs to depend on a mold with an undercut shape, but this processing is impossible in the existing press-molding device. Meanwhile, in the press-molding device 30 of the present embodiment, the combination of the cam mechanism 40 and the compression blocks 25 34a and 34b enables a configuration using a mold with an undercut shape as described above.

Furthermore, in the press-molding method of the embodiment, the preform in which the side walls 23a and 23b are longer than the side walls 13a and 13b of the press-molded article 10 is prepared as the preform 20. However, the preform 20 is not limited to this.

Specifically, in the press-molding method of the present invention, it is only necessary that the preform 20 with a larger peripheral length than the peripheral length of the punch 31 is arranged on the punch 31 when the second step is performed in parallel with the third step as described above. Accordingly, although the lengths of the flanges 25a and 25b of the preform 20 are to be set to about the same lengths as the flanges 15a and 15b of the press-molded article 10 in principle as described above, the lengths of the flanges 25a and 25b may be larger or smaller than the lengths of the flanges 15a and 15b of the press-molded article 10 (see FIG. 1) to some extent, on the premise that the preform 20 has a longer peripheral length than the peripheral 45 length of the punch 31.

		The invention claimed is:	
		1. A method for manufacturing a second bent plate body with a hat-shape by in-plane compressing a first bent plate body with a hat-shape between a first mold and a second mold, over a range from a side wall forming a crown portion of the hat shape in the first bent plate body to a flange of the hat shape, along a peripheral length direction of the hat shape,	
		wherein	
		the first mold is formed of a stationary punch which	
		comprises: a first wall surface formed to correspond to	

17

a side wall of the second bent plate body; and a second wall surface formed to correspond to a flange of the second bent plate body,
the first wall surface and the second wall surface are continuous with each other to form a first corner, 5 the second mold is formed of a die which comprises: a third wall surface in parallel to the first wall surface; and a fourth wall surface parallel to the second wall surface,
the third wall surface and the fourth wall surface are continuous with each other to form a second corner portion,
the method comprising:

a first step of disposing the side wall of the first bent plate body between the first wall surface and the third wall surface and disposing the flange of the first bent plate body between the second wall surface and the fourth wall surface; 15

a second step of pressing an end of the flange on the opposite side to the first corner portion of the flange in the first bent plate body toward the first corner portion by moving the die to the stationary punch; and 20

a third step of compressing the side wall of the first bent plate body between the first wall surface and the third wall surface and the flange of the first bent plate body between the second wall surface and the fourth wall surface while the first corner portion and the second corner portion relatively come close to each other by moving the die to the stationary punch, and the second step is performed in parallel with the third step. 25

2. The method for manufacturing the second bent plate body as set forth in claim 1, wherein

the stationary punch includes an outer end surface intersecting the second wall surface on the opposite side to the first corner portion, and 35

the method further comprising:

pressing a fifth wall surface of the die against the outer end surface of the stationary punch as the first corner portion and the second corner portion relatively come close to each other. 40

3. The method for the second bent plate body as set forth in claim 1, further comprising:

pressing an end portion of the side wall on the opposite side to the first corner portion in the first bent plate body against a top portion of the stationary punch by a pad while the pad moves toward the first corner portion. 45

4. A press-molding device comprising a first mold and a second mold, wherein

the press-molding device is configured to obtain a second bent plate body with a hat-shaped cross section by in-plane compressing a first bent plate body with a hat-shaped cross section between the first mold and the second mold, 50

each of bent plate bodies comprising:

a side wall formed to correspond to a crown portion of a hat-shape and extending in a height direction of the crown portion; and

a flange formed to correspond to a brim portion of the hat-shape and extending outward from an end portion of the side wall on an open side of the crown portion to project in a direction away from the end portion, 60

18

the first mold is formed of a stationary punch which comprises:

a first wall surface formed to correspond to a side wall of the second bent plate body; and
a second wall surface formed to correspond to a flange of the second bent plate body,

the first wall surface and the second wall surface are continuous with each other to form a first corner portion,

the second mold is formed of a movable die which comprises:

a third wall surface parallel to the first wall surface; and
a fourth wall surface parallel to the second wall surface, the third wall surface and the fourth wall surface are continuous with each other to form a second corner portion,

the press-molding device further comprising:

a compression mechanism of the stationary punch and movable die configured to bring the first corner portion and the second corner portion close to each other and compress a side wall and a flange of the first bent plate body between the first wall surface and the third wall surface and between the second wall surface and the fourth wall surface;

a first pressing mechanism of the movable die configured to move toward the first corner portion to press an end portion of the flange on the opposite side to the first corner portion in the first bent plate body toward the first corner portion; and

a second pressing mechanism including a movable pad configured to move toward the first corner portion to press an end portion of the side wall on the opposite side to the first corner portion in the first bent plate body against a top portion of the stationary punch. 30

5. The press-molding device as set forth in claim 4, wherein the first pressing mechanism and the second pressing mechanism are interlocked with each other via a cam mechanism.

6. The press-molding device as set forth in claim 5, wherein

the cam mechanism intervenes between the first pressing mechanism and the second pressing mechanism, and while the second pressing mechanism moves vertically toward the stationary punch, the second pressing mechanism moves the first pressing mechanism horizontally toward the stationary punch using the cam mechanism. 40

7. The press-molding device as set forth in claim 4, wherein the stationary punch includes an outer end surface intersecting the second wall surface on the opposite side to the first corner portion,

wherein the movable die includes a fifth wall surface to come close to the outer end surface of the stationary punch as the first corner portion and the second corner portion relatively come close to each other. 55

8. The press-molding device as set forth in claim 4, wherein the movable pad is disposed to correspond to a top portion of a hat-shape of each of the bent plate bodies and is configured to press the top portion of the hat-shape against a top portion of the stationary punch while the first corner portion and the second corner portion relatively come close to each other. 60
